UNITED STATES PATENT OFFICE.

FRANK O. HAVENER, OF PARKERSBURG, WEST VIRGINIA.

CIGAR-MOISTENER.

1,086,705.

Specification of Letters Patent. Patented Feb. 10, 1914.

Application filed June 4, 1913. Serial No. 771,765.

To all whom it may concern:

Be it known that I, FRANK O. HAVENER, a citizen of the United States, residing at Parkersburg, in the county of Wood and State 5 of West Virginia, have invented certain new and useful Improvements in Cigar-Moisteners, of which the following is a specification.

My improvement relates to cigar and tobacco moistening means.

10 One object is to provide a simple and inexpensive article of the above mentioned class to be manufactured in several different sizes and cross sectional shapes, the most important and useful of which will be 15 designed for travelers wherein a neat, compact and efficient device will be much appreciated.

A further object is to provide a moistening means for cigars wherein the receptacle 20 for the moistening medium may be adjusted longitudinally for the various lengths of cigars, and which will include a simple arrangement whereby undue moisture is obviated.

25 The improvement consists broadly, in one instance, of a perforated container for a moistening pad, and further, of a receptacle of advantageous construction having the container conveniently mounted therein.

30 In the application of my idea, the perforated container could be made in suitable forms to fit various types of cigar cases to provide a false bottom for the latter and upon which the cigars in boxes could be placed.

35 More specifically my invention consists of an outer receptacle having an adjustable telescopic cover, one or more vent holes in the upper portion thereof, one or more vent 40 holes in the lower portion of the cover, the said holes in the receptacle and cover to register under certain conditions; and a spring held removable container for the moistening pad.

45 Before referring specifically to the improvement I wish to state that the form here shown and described is my at present preferred form of humidor for travelers, of convenient size, the material to be of a light 50 non-corrosive nature.

I do not expect to confine myself to any particular size, shape, or proportion, for minor details of construction, as long as I do not depart from the broad principle of 55 the improvement as set forth in the annexed claims.

Referring to the drawings: Figure 1 represents an assembled longitudinal elevation of the device, the telescopic members being represented at the maximum closed position. Fig. 2 is a perspective view of the assembled inner container for the moistening means. Fig. 3 is a plan view of the same showing the interior of the container for the moistening pad, the bottom perforated plate and the pad being removed. Fig. 4 is a view of the interior of the bottom perforated plate of the receptacle, and Fig. 5 is a form of moisture containing pad.

Referring more specifically to the drawings in which like reference characters denote like parts in the several views, A indicates an outer receptacle having a telescopic cover B, the said cover being provided with a vent hole C and the said outer receptacle with a vent hole D. Yieldably held in place by the spring E is the inner container for the moisture medium, the said container consisting of a flanged top portion F (the same shape in plan view as the cross section 60 of the receptacle A) provided with a plurality of perforations G in the top wall thereof. In the side walls of said top portion F are rectangular slots H. A bottom portion I is also flanged in a manner similar 65 to the top portion and also provided with a plurality of perforations J. The said bottom portion I is of sufficient diameter and the proper cross section to establish a neat sliding fit within the top portion F. The 70 upset flanged side walls K of the bottom portion I have rectangular cut outs L registering with the rectangular slots H in the periphery or side walls of the top portion F. The said cut outs are for the purpose 75 of allowing the spring E to be freely expanded or contracted as required.

In the assembled view, M represents the moisture containing pad shown in detail in Fig. 5. This pad may be made of any desired absorbent material and is to be mounted as shown within the top and above the bottom annular flanged plates of the container, the said plates being held together by a central screw N having any form of flat 80 knob end, as for instance that represented at O, the object being to provide a means for withdrawing the container from the cover portion of the receptacle against the action of the spring E. This spring is flat 85 in cross section and bent in a substantially circular form with two outwardly protrud-

- ing ears E' as shown. The spring is mounted within and extends through the slots H and the cut outs L in the walls of the top and bottom portions F and I, respectively, 5 and by reason of the spring being cut at E² it is free to be compressed or to expand in a manner to secure the said container yieldably within the telescopic cover of the outer receptacle.
- 10 The manufacture of this article will be very cheap as it can be made exclusively by blanking and forming dies of stock sizes and shapes. It will be very useful and convenient for cigar smokers as, by reason of its 15 telescopic principles any size cigars may be accommodated and the degree of moisture regulated by simply moving the two members of the outer receptacle until the air holes or vents aforementioned register or by 20 returning them to a staggered position.
- The space occupied by the spring retainer acts as an air space between the moistener and the cigars, and also prevents the cigars from coming in direct contact with the moistener should the humidor be laid on its side or be inadvertently placed up side down.
- Having described my invention, I claim:
1. In combination with a receptacle, a 25 telescopic container for a moistening pad, a spring mounted within the said container, the said spring extending through openings in the side walls of the telescopic container 30

members in a manner to support the said container for the moistener by reason of its bearing against the walls of the said receptacle. 35

2. In a removable container for a moistening means, the combination of a compressible spring mounted within the said container, two flanged telescopic members provided with openings in their side walls or flanged portions and forming the said container, and a connecting means for the said members, the above mentioned spring protruding through the said openings in the 40 side walls of the telescopic members.

3. In combination with a receptacle, of a spring retained container for a moistening means, the said container consisting of perforated top and bottom annular flanged members one member being slidably mounted within the other in a manner to form a spring retaining space between the perforated portions of the said members, said space serving to receive a spring, and as an air 45 space between the moistening pad or means and the contents of the receptacle.

In testimony whereof I affix my signature in presence of two witnesses.

FRANK O. HAVENER.
